UNITED STATES PATENT OFFICE.

ADELPH KNESCH, OF RULE, TEXAS.

LOCK AND LATCH.

Application filed May 21, 1926. Serial No. 110,796.

This invention relates to a lock, the general object of the invention being to provide a simple lock for use on barn doors, garages and the like where the lock is manipulated 5 from the exterior of the building so that knobs are not necessary.

This invention also consists in certain other features of construction and in the combination and arrangement of the several parts, to 10 be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation of a portion of a door and its frame showing the invention in 20 use.

Figure 2 is a view of the lock with the cover removed and the bolt projected.

Figure 3 is a similar view but showing the bolt retracted.

25 Figure 4 is a section on line 4—4 of Figure 2.

Figure 5 is a section on line 5—5 of Figure 2.

Figure 6 is a view of the key operated member.

Figure 7 is a view of the locking tumbler.

Figure 8 is a view of the bolt.

In these views 1 indicates the casing of the lock and 2 its cover, these parts being adapted 35 to be fastened to a door or other barrier shown at A by the bolts 3, the nuts 4 of which are arranged on the inside of the door so that they cannot be taken off from the exterior of the building when the door is locked. A bolt

40 5 passes through the casing, with its ends projecting from each end thereof and this bolt is normally held in retracted position by a coiled spring 6 placed in an opening 7 formed in the bolt and having one end engaging an 45 end wall of said opening and its other end engaging a pin 8 which is carried by the casing and extends into said opening. This bolt has a pair of notches in its upper edge, as shown at 9 and 10. A locking tumbler 11 is

50 vertically movable in a guideway 12 formed in the casing, the lower end of the guideway opening out through the bottom of the casing so that the tumbler can be raised by the finger of the hand of the operator. This tumbler 55 will, under the action of gravity, drop into

one of the notches 9 or 10 as the bolt is moved to place either one of the notches in alignment with the tumbler, the tumbler having a notch 13 therein through which the bolt passes. An L-shaped key operated tumbler 14 is vertically movable in a horizontal guideway 15 in the casing, one end of this guideway being enlarged so that this end is of the same depth as the guideway 12 and the arm 14' of the tumbler 14 engages this enlarged part of the guideway when the tumbler is retracted but will engage the upper end of the guideway 12 when the tumbler is projected. When in this latter position, the arm 14' will engage the top of the tumbler 11 and thus prevent vertical movement of said tumbler 11 and will hold said tumbler in engagement with one of the notches 9 or 10.

The tumbler 14 is provided with a notch 16 for engagement by the ward of a key placed 75 in the keyhole 17 of the lock.

The rear end of the bolt 5 forms a handle and by raising the tumbler 11 by inserting the finger into the lower end of the guideway 12, the bolt can be pushed forwardly 80 until one end thereof engages the keeper recess B in the frame B' of the door. As soon as the notch 9 comes under the upper part of the tumbler 11, said tumbler will drop into the notch and thus hold the bolt projected and with the spring 6 under tension. Thus the door will be locked, but it can be unlocked by simply pushing up the tumbler 11 which will permit the spring 6 to move the bolt to retracted position and the bolt 90 will be held in this position by the tumbler dropping into the notch 10. If the door is to be locked to prevent entrance by a thief or other unauthorized person, after the bolt has been projected, as before explained, a key is inserted in the keyhole 17 and turned to project the tumbler 14 so that its arm 14' will pass over the top of the tumbler 11 and thus prevent said tumbler 11 from being pushed upwardly to release the bolt. Then 100 to unlock the door, it is necessary to insert the key and retract the tumbler 14 after which the tumbler 11 is raised to permit the spring to retract the bolt.

It is thought from the foregoing description that the advantages and novel features of my invention will be readily apparent.

I desire it to be understood that I may make changes in the construction and in the combination and arrangement of the several 110

parts, provided that such changes fall within the scope of the appended claim.

What I claim is:—

A lock of the character described comprising a casing having a longitudinal passage formed therethrough, a bolt formed with an elongated opening and mounted for slidable movement in the passage with its ends projecting beyond the ends of the casing in a manner whereby one end provides a handle, a pin secured to the casing and extending into the opening, a coil spring positioned in the opening and having its end convolutions engaging the pin and one end of said opening for normally maintaining the bolt in a retracted position, said bolt being formed with spaced parallel notches, said casing having a vertically arranged slideway having its low-

er end open, said slideway communicating with the longitudinal passage, a tumbler mounted in said slideway and operable by placing a finger in said opening and adapted for engagement with either one of said notches to retain said bolt in a projected or retracted position, said casing being provided with a horizontal guide-way, a substantially L-shaped locking tumbler provided with a notch and having one arm thereof mounted for slidable movement in said horizontal guide-way, and means engageable with said locking tumbler and within the notch thereof for moving said locking tumbler in the path of the first mentioned tumbler for locking the latter in the notches of said bolt.

In testimony whereof I affix my signature.
ADOLPH KNESCH.
